FURNITURE PAD

Alfred C. Korte, St. Louis, Mo., assignor to Metal-craft Corporation, St. Louis, Mo., a corporation of Missouri

Application February 27, 1933, Serial No. 658,848

5 Claims. (Cl. 45—137)

This invention relates to furniture tips and particularly to non-rotatable pads made of resilient material such as rubber.

It is the object of this invention to produce a generally new and improved resilient furniture pad of the simplest and most durable character.

The invention will be better understood upon reference to the accompanying drawing, in which Figure 1 shows a leg for a chair or similar article 10 having a pad of my invention applied thereto.

Figure 2 shows a sectional view of the device shown in Figure 1, the section being taken along lines 2—2 of Figure 1, looking in the direction of the arrows.

15 The reference numeral 1 indicates a tubular sheet metal member forming a chair leg or similar article. The end of the leg is slightly reduced and cut away at 2 to form a pair of opposite projecting extensions 3. These extensions 20 are flattened out so that they lie in parallel planes, and are perforated to receive the pintle 4. The pintle is formed of sheet metal, curled into a cylindrical formation and flanged at one end, prior to assembly.

25 The rubber pad 5 is formed from medium soft rubber tubing stock as regularly furnished by the rubber factories for numerous purposes. The stock is cut into lengths as indicated in Figure 2 so as to be squeezed in between the projections 3, the fit being tight enough so as to counteract the tendency to roll if the chair is pushed along the floor. The size of the inside of the tubing is such that the pintle 4 may be passed thru the 30 opening without difficulty, but not loose enough to form a free bearing fit, the friction of the tight fit assists in preventing undesired rotation.

35 After assembly the remaining end of the pintle is bent or riveted over into a flange the same as indicated in Figure 2 so that both ends are alike 40 and the pad is permanently prevented from being disassembled from the chair leg after the riveting operation, the pintle 4 is prevented by friction from rotation within the openings of the two projections 3 and the pintle 4 with the 45 rubber pad is sufficient to prevent rotation of the pad. When one side becomes worn, it is possible to twist the pad around to turn a new side to the bottom, so that it may be completely worn out all around before the metal projections come 50 in contact with the floor.

When the pad is completely worn out it may

be cut off and a new one inserted without removing the pintle by simply slitting one side of the new pad. When the new pad is squeezed into place between the projections 3, the friction together with the normal resiliency of the rubber will hold the pad in place. However, when the original pad is replaced by a new one in this manner the slit should generally be placed at the top.

I claim:

1. In a device of the class described, a furniture leg in the form of a sheet metal tube, a pair of integral parallel projections at one end of said tube, opposite perforations in said projections, a section of rubber tubing located between said projections and having the opening therein registering with said perforations, and a pintle mounted in said perforations and passing thru the opening in said section of rubber tubing. 10

2. In a device of the class described, a sheet metal tube, opposite sections being cut out at the end of said tube to form parallel similar projections, opposite perforations in said projections, a section of rubber tubing tightly fitted between the projections and a pintle mounted in said perforations and passing thru said section of rubber tubing. 15 20

3. In a device of the class described, a sheet metal tube, opposite parallel projections at one end of said tube, a section of extruded rubber tubing mounted between said projections, a pintle passing thru the perforations in said projections and said tube and frictional means normally preventing the rotation of said section of rubber tubing. 25 30 35

4. In a device of the class described, a furniture leg in the form of a sheet metal tube, integral parallel projecting portions oppositely located at one end of the tube, perforations in said projection, a pintle extending thru said perforations and a resilient pad mounted on said pintle. 40

5. In a device of the class described, a sheet metal tube, opposite parallel projections on one end of said tube, perforations in said projections, a pad comprising a section of extruded rubber tubing mounted between said projections and a substantially cylindrical sheet metal pintle passing thru said perforations and said tubing. 45 50

ALFRED C. KORTE.
